United States Patent Office

Des. 217,137
Patented Apr. 14, 1970

217,137

CONTAINER CAP

John R. Howard, Lombard, Ill., assignor to Container Corporation of America, Chicago, Ill., a corporation of Delaware

Filed June 3, 1969, Ser. No. 17,500

Term of patent 14 years

Int. Cl. D9—02

U.S. Cl. D9—285

I claim:

The ornamental design for a container cap, as shown.
